[57] CLAIM

The ornamental design for an auto wiring manifold, as shown and described.

DESCRIPTION

FIG. 1 is a front elevational view of an auto wiring manifold showing my new design;

FIG. 2 is a top plan view thereof;

FIG. 3 is a rear elevational view thereof;

FIG. 4 is a bottom plan view thereof;

FIG. 5 is an elevational view thereof as seen from the right of FIG. 1; and

FIG. 6 is an elevational view thereof as seen from the left of FIG. 3.

The wires are shown in broken lines for purposes of illustration only.
